TOY HORSE

Alexander J. Middler, Detroit, Mich.

Application April 28, 1945, Serial No. 590,898

6 Claims. (Cl. 280—1.2)

1

This invention relates to toy horses which may be ridden by a child and has for its object to provide a toy of this kind which will be propelled by motions of the body of the rider in simulation of riding a live horse.

An object of this invention is to provide a toy mounted on wheels and having a crankshaft with at least one crank throw for rotation of the wheels, the connecting rods for said crankshaft being so arranged that when the rider imposes his weight on the crankshaft through his feet the wheels will be rotated through approximately 180° and when he imposes his weight on the crankshaft by seating himself the wheels will be rotated through a second 180° thereby rotating the crankshaft to the starting position. In other words, the rear end of the body is pivotally attached to the crank of the crankshaft so that it rises and falls with rotation of the crank and consequently may be used to drive the crank through half a rotation. A shifting of the weight of the rider from the body to a linkage connected to the crank, by alternately seating himself on the body and standing in footrests simulating stirrups on the linkage, thus causes rotation of the crank through successive half revolutions and, therefore, through continuous revolutions. Alternate shifting of the weight of the rider from his feet to his seat thus causes continuous rotation of the wheels and propulsion of the toy horse.

A specific object of the invention is to provide a simplified form of the invention in which the crankshaft connects the rear wheels and has three crank throws, one of the throws being connected to foot rests and the other two being journaled jointly in the body of the horse and in rear wheels supporting and propelling the body.

Another object is to provide a crankshaft connecting the rear wheels and having a single crank throw, this single throw being connected to a connecting rod which carries the weight of the body directly and to footrests which are also connected to the crank throw through a linkage for alternate operation of the crankshaft by the imposition of the weight of a rider on the body then on the foot rests.

A further object is to provide a drive, as above described, in which the crankshaft is so related to its actuating linkages that the tendency to stop at a dead center will be minimized.

A still further object is to provide a toy horse as above described having a single front wheel mounted for steering movements and means for steering this wheel comprising handles or reins located at or near the horse's mouth.

2

Other objects and advantages will become hereinafter more fully apparent as reference is had to the accompanying drawings in which

Figure 1 is a vertical longitudinal section through my improved horse showing a crankshaft having a single crank throw for the propulsion thereof.

Figure 2 is an exploded view of a part of the linkage of Figure 1.

10 Figure 3 is a horizontal section taken along the line 3—3 of Figure 1.

Figure 4 is a side elevation of the operating mechanisms shown with the stirrup in depressed position, and

15 Figure 5 is a view similar to Figure 4 with the stirrup shown in elevated position.

More particularly, 1 indicates the body of a toy horse which is hollow in the interests of lightness of construction and in order to house the linkages hereinafter described. Pivotally secured internally of the body 1 at an intermediate point in the height and near the front end thereof are dual main supporting members 2 which parallel each other in mutually spaced relation and which 20 extend downwardly and rearwardly to the region of rear wheels. A crank shaft 3 having a single crank throw is journaled in the supporting members 2, the two supports being located on opposite sides of the crank throw. Two spaced rear wheels 4 are fixedly mounted on the crankshaft 3 for rotation therewith. Pivotally connected at 12 to the interior of the body 1 above the crankshaft 3 is an elongated connecting rod 5 which is journaled at its lower end on the throw of the 25 crankshaft 3. It will be noted that the pivot 12 is slightly rearwardly of a vertical line which intersects the axis of the crankshaft 3.

Intermediate the length of the connecting rod 5 an actuating link or lever 6 is pivotally connected thereto, this lever being fulcrumed intermediate its length by a roller 7 rotatably supported by a pin 8 which connects the two supporting members 2. A retainer 9 secured to the lever 6 forms a slot for contained travel of the lever on the roller.

The lever 6 has foot rest supports 10 pivotally connected thereto and depending therefrom, a bar 11 extending laterally from each side of the supports 10 serving as rests for the feet of the rider.

30 A single front wheel 13 has an axle 14 journaled in a yoke 15 which is secured onto a substantially vertical steering shaft 16. A bearing 17 carried by the lower part of the body 1 as a thrust bearing and a second bearing 18 vertically above and aligned with the bearing 17 support

35

the shaft 16 within the body 1. The shaft 16 is bent at its upper end and a cross-shaft 19 is secured transversely of the shaft 16 in such manner as to form steering handles. The bend of the shaft 16 is at a height such that the handles 19 will extend outwardly from a slot 20 in simulation of the mouth of the horse.

The operation is as follows: When a rider is seated astride the horse 1 with his feet resting lightly on the foot rests 11 substantially all of his weight will be applied to the pin 12, the connecting rod 5 and the crankshaft 3 which will cause the throw of the crank to find a position below the axis of the crankshaft. The pin 12 extends from one side of the interior of the body to the other and is firmly anchored therein at each end so that the weight of the rear part of the body is transferred to rods 5 by the pin 12. Whether the lowermost position is vertically below the axis of the crankshaft will depend on the relative vertical position of the pivot 12. The off-centering effect can be varied by selection of its position. If the pivot 12 is vertically above the axis of the crankshaft at the end of its downward stroke then the crank throw will be vertically below it. As illustrated in Figure 7, the pivot is slightly rearwardly of this vertical line V—V, so that the axis of the crank-pin will come to rest almost vertically below the axis of the crankshaft but very slightly in front of it. When the rider then shifts his weight onto the foot-rests 11 the lever 6 is rocked in a clockwise direction about the pin 8 and exerts an upward force on the pivot 5b in the direction of the arrow c, as indicated in Figure 7, this arrow indicating a tangent to a circle having its center at the top of roller 8 and a radius from that point to the pivot 5b. Since the pin 12 is fixed in the body this force acts to swing the bottom of the rod 5 to the left and upwardly thus rotating the crankshaft 3 over bottom dead center in a clockwise direction which will continue, with continued pressure on the stirrups 11, for approximately 180°.

As the rod 5 is thus elevated the rear of the body is accordingly elevated, the body being thus rocked through a vertical arc having its center at the axle 14 of the front wheel. The pin 12 is thus carried relatively forwardly over the axis of the crankshaft 3 so that when the rod 5 attains its uppermost position, as indicated in Figure 6, a vertical line through the axis of the crankshaft will correspond approximately with line A—B through the center of the pin 12 and this axis, the degree of approximation depending on just how far back of the vertical the pin 12 is set in the position indicated in Figure 7.

As the stirrups 11 are depressed the lever 6 not only rocks about the fulcrum 7 across a horizontal line through the fulcrum but also rolls on the roller 8 so that when the rod 5 attains its maximum upward position there is still a force in the lever urging the pivot 5b to the right of the line A—B which will carry the rod 5 past upper dead center by an amount indicated by the angle a. Thus, when the rider again shifts his weight from the stirrups to seated position his weight is imposed on the pin 12 and the crankshaft will continue to be driven in a clockwise position until the crankshaft reaches the position shown in Figure 7. Alternate shifting of the weight of the rider from the stirrups to the body thus causes continued rotation of the rear wheels and, hence, continued forward movement of the horse together with a rocking movement about the axle

14 and a rocking movement about the crank-shaft.

Various changes and alterations may be made without departing from the spirit of my invention and I desire to be extended protection as defined by the appended claims.

What I claim is:

1. A toy horse comprising a body adapted to sustain the weight of a rider, a front and two rear wheels supporting said body for propulsion thereof, a crankshaft having the two rear ones of said wheels mounted on the ends thereof for rotation therewith, a connecting rod rotatably connected to a throw of said crankshaft at one end and pivotally connected to the interior of said body at a point substantially vertically above the axis of said crankshaft whereby the imposition of the weight of the rider on said body causes rotation of said crankshaft and wheels through a portion of a revolution, foot rests intermediate the length of said body, and a linkage having one member pivotally supporting said foot rests and having another member pivotally connected to said one member and pivotally connected to said connecting rod intermediate the ends of said connecting rod, the last named member being fulcrumed intermediate its ends whereby the imposition of the weight of the rider on said foot rests rotates said crankshaft and wheels through the remainder of a revolution.

2. A toy vehicle comprising a body adapted to sustain the weight of a rider, two rear wheels and a front wheel supporting said body, a crank-shaft having the two rear ones of said wheels mounted on the ends thereof for rotation therewith, a connecting rod pivotally connected to the interior of said body at its upper end, the pivotal connection to said body being substantially vertically above and slightly rearwardly of the axis of the said crankshaft when said connecting rod is in lowermost position, said connecting rod being rotatably connected at its lower end to a throw of said crankshaft, dual main frame members jointly pivotally connected to the interior of said body near its front end and intermediate the height thereof, said crankshaft being journalled in said frame members at their other ends, foot rests, a rocking lever having a rolling fulcrum intermediate the ends thereof carried by said frame members, said lever pivotally supporting said foot rests at one end and being pivotally connected to said connecting rod at its other end intermediate the height of said connecting rod.

3. A toy vehicle comprising a body adapted to sustain the weight of a rider, two rear wheels and a front wheel supporting said body, a crankshaft having the two rear ones of said wheels mounted on the ends thereof for rotation therewith, a connecting rod pivotally connected to the interior of said body at its upper end, the pivotal connection to said body being substantially vertically above and slightly rearwardly of the axis of said crankshaft when said connecting rod is in lowermost position, said connecting rod being rotatably connected at its lower end to a throw of said crankshaft, dual main frame members jointly pivotally connected to the interior of said body near its front end and intermediate the height thereof, said crankshaft being journalled in said frame members at their other ends, foot rests, a lever pivotally connected at one end to said foot rests and at its other end to said connecting rods, and a roller supported between said dual frames constituting a fulcrum for said lever, said lever hav-

ing a retaining slot to maintain said roller in constant engagement therewith.

4. In a toy horse, a body constructed in simulation of the shape of a horse and upon which a rider may be seated, a steerable wheel supporting the front end of said body, spaced wheels supporting the rear of said body, said wheels being connected by a common axle through their respective centers, said axle having a single crank throw intermediate the length thereof, a divided frame member journaled at its ends on said axle adjacent each of said wheels outwardly of said crank, stirrup means intermediate said front and said rear wheels depending from and pivotally connected to one end of a rocking beam, said beam being connected at its other end through a linkage to said crank and fulcrumed on a pivot carried by said frame said linkage comprising a connecting rod pivotally connected at its upper end to the interior of said body for the support thereof and journaled at its lower end on said crank whereby when said rider is seated on the body the crank will assume one position and when said rider imposes his weight on said stirrup means the crank will assume another position approximately 180° removed from its first position, the pivot of said rocking beam with said frame being adapted to shift fore and aft during rotation of said crank thereby biasing said crank in uppermost and lowermost positions whereby said crank always stops off dead center position whether the weight of the rider is on the body or on the stirrup means.

5. A toy vehicle comprising a body adapted to sustain the weight of a rider, two rear wheels, a front steerable wheel supporting the front end of said body, a crankshaft journaled in said two rear wheels and secured thereto for rotation therewith, a substantially vertical connecting rod connected at its lower end to the throw of said crankshaft and pivotally connected at its upper end to the interior of said body for the support of the rear end of said body, a divided main frame member having its front end pivotally connected to the interior of said body near the front end of said body and having journals at its other end to receive said crankshaft, foot rests carried by links at each side of said body, said links each being pivotally connected to one end of a lever pivotally connected at its other end to a point intermediate the length of said connecting rod, said lever being arranged to fulcrum intermediate its length back and forth across a horizontal line about a roller carried by said main frame member, said foot rests when supporting the weight of a rider causing partial rotation of said lever about its fulcrum with consequent elevation of said connecting rod and rotation of said crankshaft, said body when supporting the weight of said rider depressing said connecting rod, thus causing further partial rotation of said crankshaft, said connecting rod by its movements of elevation and depression causing a corresponding elevation and depression of the rear end of said

body through an arc having its center on the axis of said front steerable wheel.

6. A toy vehicle comprising a body adapted to sustain the weight of a rider, two rear wheels, a front steerable wheel supporting the front end of said body, a crankshaft journaled in said two rear wheels and secured thereto for rotation therewith, a substantially vertical connecting rod connected at its lower end to the throw of said crankshaft and pivotally connected at its upper end to the interior of said body for the support of the rear end of said body, a divided main frame member having its front end pivotally connected to the interior of said body near the front end of said body and having journals at its other end to receive said crankshaft, foot rests carried by links at each side of said body, said links each being pivotally connected to one end of a lever pivotally connected at its other end to a point intermediate the length of said connecting rod, said lever being arranged to fulcrum intermediate its length back and forth across a horizontal line about a roller carried by said main frame member, said foot rests when depressed by the imposition of the weight of the rider rocking said lever about its fulcrum thereby elevating said connecting rod and simultaneously rolling on said roller thereby forcing the connecting rod over the upper dead center position of said crankshaft, said body when supporting the weight of said rider depressing said connecting rod, thus causing further rotation of said crankshaft to a position where the crank throw is substantially vertically below the axis of said crankshaft, said connecting rod causing an up and down movement of the rear end of said body and also an oscillating movement of said body about the axle of said front steerable wheel whereby the position of the pivotal connection of said connecting rod to said body varies with respect to a vertical line through the axis of said crankshaft during propulsion of said body.
